UNITED STATES PATENT OFFICE

101,899

DESIGN FOR A SHOE OR SIMILAR ARTICLE

Seymour Troy, New York, N. Y.

Application September 2, 1936, Serial No. 64,697

Term of patent 3½ years

To all whom it may concern:

Be it known that I, Seymour Troy, a citizen of the United States, residing in New York city, in the county of New York, in the State of New York, have invented a new, original, and ornamental Design for a Shoe or Similar Article, of which the following is a specification, reference being had to the accompanying drawing, forming part thereof.

Figure 1 is a plan view of a shoe showing my new design.

Figure 2 is a side elevation of the shoe, partly in perspective.

An outstanding feature of my design is the attractive appearance given to the shoe by the piping surrounding the entire shoe and located at substantially the same distance from the sole and shank of the shoe, the piping, however, turning upwardly near the rear portion of the shank and extending around the counter of the shoe near the upper edge thereof.

I claim:

The ornamental design for a shoe or similar article, substantially as shown and described.

SEYMOUR TROY.
